[57] ABSTRACT

A walk-in and a walk-through bobbin creel which comprises bobbin creel units each having U-shaped frames providing a structure of vertical members on each side and each member supports sets of a pair of bullhorn bobbin spool supports completely around the U-shaped frame. The take-off for the ends of the yarns is toward one respective end or the other on each side and thence to a plurality of plastic tubes contained in a bundle across the top of the frame.

BOBBIN CREEL

BACKGROUND OF THE INVENTION

1. Field of the Invention

Bobbin creels and particularly yarn creels for supporting a plurality of spools of yarn packages for delivery to the same machine.

2. Description of the Prior Art

The prior art includes many types of yarn and bobbin creels. The present creel has a particular use in the carpet industry for directing a plurality of carpet yarn through plastic tubes to a tufting machine because there are so many yarn ends feeding from one creel. Earlier creels used in the carpet industry included upright posts with horizontal runner bars on which vertical cone holders were mounted. The yarn take-off was first vertical, then horizontal through thread guides, and the yarn had to be threaded through guides at each cross member throughout the length of the creel. Many creels are this basic design. Another creel design employed tubing to conduct the yarn from the package to the machine and the yarn cone from the yarn packages were held in a nearly horizontal position to feed the yarns therefrom. It is quite common to use the bullhorn or bicycle handlebar type brackets each supporting one package on one end and the common arrangement was to convey the yarns to a take-off point near the aisle. Bobbin creels which are designed to put a lot of yarn packages (bobbins) in a small space are very hard to service and require a great deal of reaching in and reaching around and while they provide more yarn packages (bobbins) in less space there is a big problem of how to service these without crawling and bending around into many different awkward time consuming and tiring positions. On the other hand, bobbin creels which are designed mainly from the standpoint of service and easy reach take up a great deal of space around the machines in the mill and do not provide very many packages of yarn for the amount of space used. There is a demand in many mills, particularly in carpet tufting plants, for a bobbin creel which provides a very usable number of yarn packages in the space but at the same time is easy to service.

SUMMARY OF THE INVENTION

The bobbin creel is arcuate in construction and is made from several arcuate frames which extend from one side across the top and then down the other side providing what might be considered a grape arbor or bower arrangement. The handlebar or bullhorn yarn supports are arranged on each side in the middle of the structure and extend all the way from the bottom across the top and down the other side and both ends of the frame are completely free of any bobbin supports. The yarns are led in a converging direction from each bullhorn or handlebar to that respective side on one end or the other and then into plastic tubing across the top of the bobbin creel. This arrangement provides a very accessible walk-through enclosure with bobbins in the middle on both sides easily accessible by one man.

An object of this invention is to provide an open bobbin creel with bobbins supported on both sides in the middle and the top thereof.

Another advantage of this bobbin creel is in the simplicity of construction which may be a basic metal

frame from three-U-shaped frame members mounted on horizontal mount supports with the metal frame member being tubing on which is welded the bullhorn bobbin spool supports.

5 BRIEF DESCRIPTION OF THE DRAWINGS

FIG. 1 is a perspective view of a typical bobbin creel made in accordance with this invention.

FIG. 2 is a cross-sectional view taken along lines 2-2 in FIG. 1.

FIG. 3 is a cross-sectional view taken along lines 3-3 in FIG. 1.

DESCRIPTION OF A PREFERRED EMBODIMENT

15 A bobbin creel designated generally by reference numeral 10 in FIG. 1 is, as mentioned previously, an enclosure, which could be 6 feet high and 3 1/2 feet wide, through which one may walk from one end to the other and the yarn packages or bobbins are located in the 20 middle portion from the bottom to the top on each side and across the top of the frame. A pair of U-shaped end frame members 12, 14 constructed from metal angle iron and each with an arcuate top 16 has bottom ends 18 welded to horizontal floor supports 20 which are 25 metal angle iron members. Each U-shaped frame 12, 14 has U-shaped tube supports 24 welded by tube members 25 to the U-shaped portion 16 of each frame 12, 14.

30 A center U-shaped frame 26 (which, for example, can be 1 inch tubing) is constructed from pipe or other tubular material and has the lower end 28 welded approximately in the middle of the length of the ground support members 20. A plurality of handlebar-type or 35 bullhorn-type yarn package or bobbin support assemblies 32 are welded with the open centers 34 around the frame 26 and there are a plurality of these all the way up one side on one side of the frame 26 and across the top and down the other side from approximately just above the floor surface 36 across the upper part of 40 the U-shaped frame 26.

45 U-shaped frames 12, 14 have a plurality of holes 38 therein each having the open end of a plastic tube 40 inserted thereto to receive the yarn or yarn end 44 from a yarn package 46 which is mounted on the shaft 48 of the bullhorn assembly 32. The end 42 of tube 40 projects into the hole 38 in frames 12, 14. The yarn packages 46 are held in place by the usual retainer 50 mounted on the respective shaft 48 of each bullhorn assembly 32 to be detached therefrom to be replaced by a fresh yarn package 46 when empty. Retainer 50 has an attachment collar 52 held on the shaft 48 by a set screw. A bent spring member 54 inserts into a yarn cone core 56 which is standard in a yarn package.

55 The yarn end 44 coming from yarn packages 46 mounted on the bullhorn assembly 32 and facing toward the end with the U-shaped frame member 14 or led to the U-shaped member 14 and thence conducted thru the tube 40 which collects in a bundle through the U-shaped supports 24 on the top of frame 14 and thence across a U-shaped support 24 on top of frame 26 and U-shaped support 24 on top of frame 12. Those 60 yarn packages 46 and the ends thereof 44 which are facing in a direction toward the other end at the U-shaped frame member 12 and a tubing from the frame member 12 is collected from each hole 38 into a bundle supported in the U-shaped support 24 on top of frame member 12. Those 65 arrangement keeps the multiplicity of

a considerable number of the yarn ends 44 directed along the sides of the respective sides of the bobbin creel 10 and leaves an open passageway from one end at the U-shaped frame member 12 to the other end of the U-shaped frame member 14 for servicing the yarn packages 46 which is done by one man walking and standing in a normal position without having to reach in or reach through or climb around in any awkward and difficult positions.

As seen in FIG. 2, while the shafts 48 have a slight angle of inclination A (less than 30°) from the horizontal the yarn ends 44 travel without intersection to the respective U-shaped frame and leave plenty of space and opening for service and for correction of any broken yarn ends or any other problems which may arise.

While I have shown and described a particular embodiment of my invention in the form of a preferred example this is by way of illustration only since there are various alterations, changes, deviations, eliminations, additions, omissions, revisions, and departures which may be made in the preferred embodiment without departing from the scope of my invention as defined by the appended Claims.

I claim:

1. In a bobbin creel:
  - a. a bobbin creel structure open from opposite ends and comprising side frame members and top frame members extending thereacross defining a passageway from one end thereof to the other,
  - b. yarn package supports mounted on each side of said frame intermediate the length thereof and removably supporting yarn packages, there being yarn packages on each support having the continuous yarns therefrom led to one end of the frame on the same side without the yarn crossing said passageway,
  - c. a plurality of yarn conducting guides on said frame having the entrances thereto on a respective side to receive the end of a yarn therein,
  - d. said yarn guides extending from the point where each respective guide picks up its yarn thence to the top of the structure without crossing the passageway,
  - e. said yarn guides being flexible conduits such as plastic tubing having the entrance thereto on the structure,
  - f. said flexible conduits extending in a bundle across the top frame members of said structure.

2. The device in claim 1: said structure being U-shaped and said top frame members being arcuate from one side to the other.

3. The device in claim 2: there being yarn package supports spaced from the bottom to top on each side.

4. The device in claim 3: each yarn support comprising at least two members extending in opposite directions toward one end and each supporting a yarn package having the yarn therefrom directed toward a respective end of the structure.

5. The device in claim 3: there being a pair of yarn supports directed toward opposite ends of the creel.

6. The device in claim 3: said yarn package supports comprising a pair of U-shaped members each supporting a yarn package, the U-shaped members on each side being directed toward one end and extending in a direction to cause said yarn from the yarn package thereon to converge at that end on one side.

7. The device in claim 1: there being an entrance for yarn at each of the opposite ends near each corner of said frame and said yarns extending to a respective end on its side without crossing the passageway of the yarn on the other end.

8. The device in claim 1: said structure being U-shaped and said top frame members being arcuate from one side to the other.

9. The device in claim 8: there being yarn package supports spaced from the bottom to top on each side.

10. The device in claim 9: each yarn support comprising at least two members extending in opposite directions toward one of the opposite ends and each supporting a yarn package having the yarn therefrom directed toward a respective end of the structure.

11. The device in claim 10: there being yarn supports directed toward each of the opposite ends.

12. The device in claim 11: said yarn package supports comprising a pair of U-shaped members each supporting a yarn package, the U-shaped members on each side being directed toward one end and extending in a direction to cause said yarn from the yarn package thereon to converge at said one end on one side.

13. The device in claim 12: there being an entrance for yarn at respective opposite ends near each corner of said frame and said yarns extending to a respective end on one side without crossing the passageway or the yarn.
